UNITED STATES PATENT OFFICE.

ANDRÉ CHAPELON, OF LEVALLOIS, FRANCE.

STEAM-BOILER DRAFT-INCREASING DEVICE.

Application filed August 20, 1927, Serial No. 214,410, and in France August 21, 1926.

My invention relates to a device adapted to increase the draught of boilers for locomotives and other steam engines, while decreasing the steam pressure in the exhaust 5 pipe, a better utilization of steam in the cylinders of the engine being thus obtained because of the reduced back-pressure on the pistons.

An object of my invention is to provide 10 a device of this kind wherein the length is made relatively short to suit the characteristics of the locomotives; of such design that very efficient action is assured.

In order to make my invention clearly 15 understood I have illustrated, as examples, several embodiments of the same in the drawings appended hereto wherein:

Figure 1 shows one form of my invention.

Fig. 2 shows another form.

Figures 3, 4 and 5 show further modifications; and

Figure 6 illustrates a twyer suitable for use with the devices shown by Figures 1 to 5.

As shown by Figures 1 and 2 in the drawings appended hereto, my device consists essentially of the combination of a nozzle 1' (Figure 1) or of a series of nozzles 1', 1'', 1''' (Figure 2) provided with complete or incomplete spiders or with inside plugs, 20 and disposed in line with the exhaust pipe 3; with a cylindrical or conical nozzle 2, unobstructed inside, and located between the first nozzles and the stack 4.

The aforesaid series of nozzles will permit 35 the length of the device to be reduced sufficiently to permit the same to be mounted on a locomotive, notwithstanding restricted gauge; the last nozzle 2, whether cylindrical or conical, affording perfect operation of 40 the stack.

Where the dimensions of the boiler are suitable, the above described device can be simplified through substituting for the stack 4 and the nozzle 2 (Figure 3 or 4) the truncated portion 4' (Figure 5), the lower part 45 of which is joined to an inverted truncated cone 2', suitably designed and but little flared, so as to produce a substantial vacuum in neck A'.

The fact is proved that steam and smoke 50 exhaust is accomplished with minimized power loss when the disposition of the parts (Figure 3 or 4) is such that there is no more any suction at A between the bottom of 55 stack 4 and the outlet of nozzle 2.

I therefore unite said nozzle 2 and stack 4 by giving them new forms and proportions, like those shown at 2' and 4' (Figure 5), so that the mixing of gases and steam in nozzle 2' and exhaust thereof through stack 60 4' will take place under best possible theoretical and practical conditions.

The result from this combination is a remarkable increase of the draught, the greater indeed the more the speed of the engine is 65 increased.

My invention may also advantageously include a steam exhaust twyer or pipe as illustrated in Fig. 6 which in practice is placed over the exhaust pipe 3 and between the 70 same and the nozzle or nozzles in line therewith. This twyer is conical inside, the interior sloping about 30° and at its upper end it terminates in an inside cylindrical portion B of moderate length. It also has 75 at its upper end a number of internal projections C which are triangular in cross-section, the apex being presented toward the exhaust pipe 3 so as to divide and flare 80 out the steam jet.

Having now particularly ascertained and described the nature of my said invention as well as the manner in which the same is to be performed, I declare that what I claim is.

Claims:—

1. A device for increasing the draught of locomotives comprising one or more nozzles in line with the steam exhaust pipe, said nozzles having means inside to divide and spread the exhaust steam, another nozzle 90 unobstructed inside, and an exhaust twyer conical inside and having a cylindrical portion and projections on its interior to divide the exhaust steam and spread the same.

2. A device for increasing the draught of 95 locomotive boilers comprising one or more nozzles between the stack and the exhaust pipe, said nozzles having means inside to divide and spread the exhaust steam, the stack terminating at its lower end above the 100 nozzles in an inverted truncated section, and an exhaust twyer conical in shape having a cylindrical section on its interior at the top carrying inside devices to divide and spread the exhaust steam from the exhaust 105 pipe.

In testimony whereof I affix my signature.

ANDRÉ CHAPELON.
